UNITED STATES PATENT OFFICE

167,561

REFRIGERATOR DOOR HANDLE

Donald Dailey, Center Township, Vanderburgh County, and Charles D. Dushek, Evansville, Ind., assignors to Servel, Inc., New York, N. Y., a corporation of Delaware

Application May 6, 1952, Serial No. 19,621

Term of patent 14 years

(Cl. D67—3)

To all whom it may concern:

Be it known that we, Donald Dailey, a citizen of the United States of America residing at Old Petersburgh Road, Center Township, in the county of Vanderburgh and State of Indiana, and Charles D. Dushek, residing at Evansville, in the county of Vanderburgh and State of Indiana, have invented a new, original, and ornamental Design for a Refrigerator Door Handle, of which the following is a specification, reference being had to the accompanying drawing, forming part thereof.

Fig. 1 is a perspective of a refrigerator door handle, showing our new design;

Fig. 2 is a front elevation thereof;

Fig. 3 is a side elevation of the door handle.

We claim:

The ornamental design for a refrigerator door handle, as shown.

DONALD DAILEY.

CHARLES D. DUSHEK.
